RAILWAY TRAFFIC CONTROLLING APPARATUS

Filed Sept. 29, 1928

UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed September 29, 1928. Serial No. 309,215.

My invention relates to railway traffic controlling apparatus, and particularly to train-carried apparatus of the type wherein the brakes of the train are controlled jointly by 5 traffic conditions in advance and the speed of the train.

I will describe one form of train carried apparatus embodying my invention, and will then point out the novel features thereof in 10 claims.

The accompanying drawing is a view, partly diagrammatic and partly in section, showing one form of apparatus embodying my invention.

15 Referring to the drawing, the reference character R designates a train control relay which, as here shown, is of the induction motor type comprising two stator windings 1 and 2 and a rotor 3. The rotor operates 20 contact fingers 4 and 5. This relay is controlled by traffic conditions in advance of the train in such manner that when traffic conditions are clear, so that high speed is permissible, the contact fingers 4 and 5 are swung 25 to the right; under caution traffic conditions, that is, conditions requiring a medium speed limit, the contact fingers are swung to the left; and under danger traffic conditions, that is, conditions requiring a low speed limit, the 30 contact fingers occupy their intermediate or vertical positions. The apparatus for controlling the relay R forms no part of my present invention and is therefore omitted from the drawing.

35 The train is provided with a speed limit indicator or cab signal S, comprising three lamps S^H, S^M and S^L, which lamps when lighted indicate high speed, medium speed and low speed, respectively. The circuit for the high speed lamp S^H is from terminal B of a suitable source of current, through contact 4-4^a of relay R, wires 6 and 6^a, and lamps S^H to terminal O of the same source of current. The circuit for lamp S^M is similar to the circuit just traced, except that it includes contact 4-4^b of relay R and wires 11 and 12. The circuit for lamp S^L is from terminal B, through contact 5-5^a of relay R, wires 14, 15 and 16, and lamp S^L to terminal O. It 50 will be seen, therefore, that lamp S^H is lighted when the relay R is energized in the high speed direction, lamp S^M is lighted when the relay is energized in the medium speed direc-

tion, and the lamp S^L is lighted when the relay is deenergized. 55

The train control relay R also controls speed governing mechanism comprising a high speed magnet H, a medium speed magnet M, and a low speed magnet L. These magnets, together with a centrifugal device 60 C, control a pneumatic relay comprising a pair of contacts 25 and 26, which contacts in turn control a valve magnet A, and the valve magnet A automatically controls the air brake apparatus on the train. 65

The high speed magnet H operates a high speed pilot valve B^H, the medium speed magnet M operates a medium speed pilot valve B^M, and the low speed magnet L operates a low speed pilot valve B^L. The speed governing mechanism also comprises a normally closed high speed valve V^H, a normally closed medium speed valve V^M, and a normally closed low speed valve V^L. Each valve V is biased to the closed position by a spring 42. 70 These valves are controlled by tappets 41 mounted in a crosshead 40 which is operated by the centrifugal device C. The centrifugal device is operatively connected with an axle of the train through the medium of bevelled gears 38 and 39, as well as other mechanical driving mechanism not shown in the drawing. The valves V are operated in such manner that when the train exceeds a given low speed limit valve V^L is opened, when the 75 train exceeds a given medium speed limit the valve V^M is opened, and when a train exceeds a given high speed limit the valve V^H is opened. 80

The brake controlling contacts 25 and 26 90 are operated by a piston 44 responsive to variations of fluid pressure in a cylinder 43 which is always connected by pipe 45 with the high speed valve V^H. When the high speed magnet H is energized, cylinder 43 is 95 connected with a pipe P through a restricted orifice 50; the pipe P is connected with a source of fluid pressure which is not shown in the drawing. When the high speed magnet H is de-energized and the medium speed magnet M is energized, the cylinder 43 is connected with pipe P, and also with the medium speed valve V^M through a pipe 46. When magnets H and M are de-energized and the low speed magnet L is also deenergized, the cylinder 43 is connected with at- 100 105

mosphere through a port 49; but when magnets H and M are de-energized and magnet L is energized, the cylinder 43 is connected with pipe P, and also with the low speed valve V¹ through a pipe 47.

A restricted orifice 51 is preferably interposed between cylinder 43 and pipe 45 to cause a delay of three or four seconds between the opening of cylinder 43 to atmosphere and the movement of piston 44. A check valve 52 is placed in multiple with this orifice to permit quick charging of cylinder 43 to full pressure.

The circuit for magnet A is from terminal B, through contact 25, wire 27, contact 28 of acknowledging switch E, wire 29, winding of magnet A, wire 30, and contact 26 to terminal Q.

20 The magnet A controls a valve 31 in such manner that when this magnet is energized, pipe P, which leads to the source of fluid pressure, is connected with a timing reservoir 32. A restricted orifice 53 is interposed between reservoir 32 and valve 31 to delay the 25 discharge of this reservoir, and a check valve 54 is connected in multiple with the orifice 53 to permit quick charging of the reservoir. The timing reservoir 32 controls a piston 33 which operates a valve 34, and the valve 30 34 in turn controls the pressure in a pipe 35 leading to an automatic brake application valve which is not shown in the drawing. When the timing reservoir 32 is charged with 35 fluid pressure, piston 33 is held in its uppermost position, so that valve 34 is closed to prevent the discharge of air from the pipe 35. Under this condition there is no automatic application of the brakes. When magnet A becomes de-energized, valve 31 reverses 40 to disconnect the timing reservoir 32 from pipe P and to connect this reservoir with atmosphere through a warning whistle 37 and a restricted port 36 which creates back pressure for the whistle. After a time interval 45 which depends on the relative sizes of the timing reservoir and the orifice 53, piston 33 will drop, thereby reversing valve 34, so that pipe 35 will be connected with atmosphere to cause an automatic application of the 50 brakes.

50 The electrical portions of the apparatus are controlled in part by a pneumatic relay D comprising a diaphragm 48 which is subjected to pressure when an automatic application 55 of the brakes occurs. This diaphragm controls a contact 21 which is normally closed, but which opens when the diaphragm is exposed to fluid pressure.

The electrical apparatus also includes an acknowledging switch E comprising two contacts 20 and 28, the former of which is normally open and the latter of which is normally closed. When the engineer operates the acknowledging switch E, contact 20 becomes closed and contact 28 becomes opened.

The operation of the apparatus is as follows: As shown in the drawing, relay R is energized in the normal or clear direction, so that the high speed indicator lamp S^H is lighted. The high speed magnet H is also energized by virtue of a circuit which passes from terminal B, through contact 4-4^a of relay R, wires 6 and 8, and the winding of magnet H to terminal O. The pilot valve B^H is therefore in such position that the cylinder 43 and valve B^H are connected with the supply pipe P through the restricted orifice 50, and 43 is cut off from communication with valves V^M and V^L . Magnets M and L are both de-energized, with the result that the medium speed valve V^M and the low speed valve V^L are connected to atmosphere through port 49. If the train exceeds a given high speed, the crosshead 40 will open the high speed valve V^H , and cylinder 43 will then be opened to atmosphere. After an interval of three or four seconds, piston 44 will move downwardly to open the contacts 25 and 26 and so de-energize the brake controlling magnet A. Valve 31 will then reverse, causing whistle 37 to blow for several seconds, after which valve 34 will reverse to cause an application of the brakes.

I will now assume that the train control relay becomes energized in the reverse direction in response to caution traffic conditions in advance. The medium speed indicator lamp S^M will then become lighted and the high speed lamp S^H will become extinguished. The circuit for the high speed magnet H will be opened at contact 4-4^a of relay R, and the circuit for the medium speed magnet M will become closed, this circuit being from terminal B, through contact 4-4^b of relay R, wires 11 and 13, and winding of magnet M to terminal O. The pilot valve B^H will then be elevated, whereas, the pilot valve B^M will be depressed, with the result that cylinder 43 will be connected with the medium speed valve V^M and also with the pressure supply pipe P. If the train exceeds a given medium speed, valve V^M will be opened to reduce the pressure in cylinder 43, with the result that after a time interval of three or four seconds, contacts 25 and 26 will open to cause an automatic application of the brakes.

I will now assume that relay R becomes de-energized in response to danger traffic conditions in advance. The opening of contact 4-4^b will deenergize the medium speed magnet M, and if the engineer takes no action the low speed magnet L will remain de-energized. Cylinder 43 will then be connected with atmosphere through port 49, and the connection to supply pipe P will be cut off by valve B^L, so that contacts 25 and 26 will be opened after a time interval to cause an automatic application of the brakes. If, however, the engineer momentarily reverses the acknowledging switch E prior to an automatic brake ap-

lication, a pick-up circuit for magnet L will be closed, which circuit passes from terminal B, through contact 5-5^a of relay R, wires 14, 15 and 19, contact 20 of acknowledging switch E, contact 21 of pneumatic relay D, wire 22, and the winding of magnet L to terminal O. When magnet L becomes energized, it will close a contact 24 which is operated by the armature of this magnet, and a stick circuit for magnet L will then become closed. This stick circuit is from terminal B, through contact 5-5^a of relay R, wires 14 and 23, contact 24, and winding of magnet L to terminal O. Magnet L will then remain energized as long as dangerous traffic conditions exist, that is, as long as relay R remains de-energized. Pilot valve B^L will now be depressed, thereby connecting cylinder 43 with the supply pipe P and also with the low speed valve V^L through pipe 47. If the train exceeds a given low speed, valve V^L will be opened to reduce the pressure in cylinder 43 and so to cause an automatic application of the brakes after the expiration of a short interval of time.

It will be noted that when the engineer reverses the acknowledging switch E, contact 28 will become open, thus requiring that this switch be restored to its normal position at once in order to avoid an automatic application due to de-energization of magnet A. It will also be noted that the acknowledgment must occur before an automatic brake application is initiated, because otherwise contact 21 will be open and will prevent the closing of the pick-up circuit for the low speed magnet L.

The purpose of the restricted orifice 51 is to prevent unnecessary blowing of whistle 37 while the train is passing over block joints and other locations where the control of relay R is unavoidably interrupted for short intervals of time.

The purpose of the restricted orifice 50 in the supply pipe P is to cause a large variation in the pressure in cylinder 43 as the result of a small movement of each valve V. I will assume that the pneumatic relay F is so adjusted that its contacts will open when the pressure in the cylinder 43 is reduced to one-half of its normal value. This will occur when the effective area of the exhaust through each valve V is approximately the same as the cross-section of the restricted orifice 50. Assuming that the orifice 50 is $\frac{1}{16}$ " in diameter, and that the effective diameter of each valve V is $\frac{1}{16}$ "; this valve need be opened only .003" in order to make its effective area equal to the area of the restricted orifice, and, of course, only an extremely small movement of the crosshead 40 is necessary to produce this amount of opening of the valve. In other words, an extremely small movement of a valve V will cause a large fluctuation in the pressure in cylinder 43. For this

reason, the differential pressure required to operate the pneumatic relay F from the closed to the open position or vice-versa, is accomplished with an extremely small change in speed, so that the speed limiting mechanism is extremely sensitive. In practice, the contacts 25 or 26 of relay F are preferably constructed in the form of the usual toggle or snap switch mechanism, so that their operation is quick and positive even though the pressure in cylinder 43 is changing slowly, thereby to avoid burning or arcing of the contacts at critical speeds.

One advantage of apparatus embodying my invention, is that the selection of speed limits and the brake application mechanism are accomplished electrically, thereby avoiding the complications inherent in the large number of valves and pipes which would be required if these functions were performed pneumatically. At the same time, I have retained the advantages of the pneumatic speed governor which is considerably more sensitive, reliable and accurate than any governor in which contacts are actuated mechanically by centrifugal force. The reason for this is that electrical contacts, to be operated reliably, require more stroke and pressure than can be developed mechanically as the result of a small change in the position of the weights of the centrifugal device due to a small increase or decrease in speed.

Although I have herein shown and described only one form of apparatus embodying my invention, it is understood that various changes and modifications may be made therein within the scope of the appended claims without departing from the spirit and scope of my invention.

Having thus described my invention, what I claim is:

1. Train control apparatus comprising a cylinder connected with a source of fluid pressure through a restricted orifice, a normally closed valve connected with said cylinder, a centrifugal device operatively connected with a wheel of the train, means operated by said centrifugal device for opening said valve when the speed of the train exceeds a given value, a movable member responsive to variations of the pressure in said cylinder, a contact operated by said member, and train governing mechanism controlled by said contact.

2. Train control apparatus comprising a cylinder, a movable member associated with said cylinder and responsive to variations of pressure therein, a contact operated by said member, train governing mechanism controlled by said contact, a plurality of valves, means for selectively connecting said cylinder with said valves, and means for opening said valves at different speeds of the train.

3. Train control apparatus comprising a cylinder, a movable member associated with

said cylinder and responsive to variations of pressure therein, a contact operated by said member, train governing mechanism controlled by said contact, a plurality of valves, 5 means for selectively connecting said cylinder with said valves, a centrifugal device operatively connected with a wheel of the train, and means operated by said device for progressively opening said valves as the speed 10 of the train increases.

4. Train control apparatus comprising a cylinder connected with a source of fluid pressure through a restricted orifice, a normally closed valve connected with said cylinder, 15 means for opening said valve when the speed of the train is above a given value, a movable member responsive to variations of the pressure in said cylinder, a contact operated by said member, and train governing mechanism 20 controlled by said contact.

5. Train control apparatus comprising a cylinder, a movable member associated with said cylinder and responsive to variations of pressure therein, a contact operated by said 25 member, train governing mechanism controlled by said contact; means for supplying fluid pressure to said cylinder through a restricted orifice, a plurality of valves, means for selectively connecting said cylinder with 30 said valves, and means for opening said valves at different speeds of the train.

6. Train control apparatus comprising a cylinder, a movable member associated with said cylinder and responsive to variations of 35 pressure therein, a contact operated by said member, train governing mechanism controlled by said contact; means for supplying fluid pressure to said cylinder through a restricted orifice, a plurality of normally closed 40 valves, means for selectively connecting said cylinder with said valves, a centrifugal device operatively connected with a wheel of the train, and means operated by said device for progressively opening said valves as the 45 speed of the train increases.

7. Train control apparatus comprising a cylinder, a movable member associated with said cylinder and responsive to variations of pressure therein, a contact operated by said 50 member, train governing mechanism controlled by said contact; a high speed valve constantly connected with said cylinder, a medium speed valve, a low speed valve, all of which valves are biased to the closed position, a high speed magnet, a medium speed magnet and a low speed magnet, means operating when said high speed magnet is energized to connect said cylinder with a source 55 of fluid pressure through a restricted orifice, 60 means operating when said medium speed magnet is energized and said high speed magnet is de-energized to connect said cylinder with said medium speed valve and with said source of fluid pressure and restricted orifice, 65 means operating when said low speed magnet

is energized and said high speed and medium speed magnets are de-energized to connect said cylinder with said low speed valve as well as with said source of pressure and restricted orifice, means operating when all of said 70 magnets are de-energized to connect said cylinder with atmosphere but not with said source of pressure; and means for opening said low speed valve when the speed of the train exceeds a given low value, said medium 75 speed valve when the speed exceeds a given medium value, and said high speed valve when the speed exceeds a given high value.

8. Train control apparatus comprising a cylinder, a movable member associated with 80 said cylinder and responsive to variations of pressure therein, a contact operated by said member, train governing mechanism controlled by said contact; a high speed valve constantly connected with said cylinder, a me- 85 dium speed valve, a low speed valve, all of which valves are biased to the closed position, a high speed magnet, a medium speed magnet and a low speed magnet, a high speed pilot valve controlled by said high speed mag- 90 net and operating when the magnet is ener- gized to connect said cylinder with a source of fluid pressure through a restricted orifice, a medium speed pilot valve controlled by said medium speed magnet and operating when 95 the magnet is energized and said high speed magnet is de-energized to connect said cylinder with said medium speed valve and with said source of fluid pressure and restricted orifice, a low speed pilot valve controlled by 100 said low speed magnet and operating when the magnet is energized and the other two magnets are de-energized to connect said cylinder with said low speed valve as well as with said fluid pressure source and restricted ori- 105 fice, said pilot valves operating when all three magnets are de-energized to connect said cylinder with atmosphere but not with said source of pressure, and means for opening said low speed valve when the speed of the 110 train exceeds a given low value, said medium speed valve when the speed exceeds a given medium value, and said high speed valve when the speed exceeds a given high value.

9. Train control apparatus comprising a cylinder, a movable member associated with said cylinder and responsive to variations of pressure therein, a contact operated by said member, train governing mechanism controlled by said contact; a high speed valve constantly connected with said cylinder, a medium speed valve, a low speed valve, all of which valves are biased to the closed position, a high speed magnet, a medium speed magnet and a low speed magnet, means operating when said high speed magnet is energized to connect said cylinder with a source of fluid pressure through a restricted orifice, means operating when said medium speed magnet is energized and said high 125 speed magnet is de-energized to connect said cylinder with said medium speed valve and with said source of fluid pressure and restricted orifice, means operating when said low speed magnet is energized and said high 130

- speed magnet is deenergized to connect said cylinder when said medium speed valve and with said source of fluid pressure and restricted orifice, means operating when said 5 low speed magnet is energized and said high speed and medium speed magnets are de-energized to connect said cylinder with said low speed valve as well as with said source of pressure and restricted orifice, means 10 operating when all of said magnets are de-energized to connect said cylinder with atmosphere but not with said source of pressure; a centrifugal device operatively connected with an axle of the train, and means 15 operated by said device for opening said low speed valve when the speed of the train exceeds a given low value, said medium speed valve when the speed exceeds a given medium value, and said high speed valve when 20 the speed exceeds a given high value.
10. Train control apparatus comprising a cylinder, a movable member associated with said cylinder and responsive to variations of pressure therein, a contact operated by 25 said member, train governing mechanism controlled by said contact; a high speed valve constantly connected with said cylinder, a medium speed valve, a low speed valve, all of which valves are biased to the closed position, a high speed magnet, a medium speed 30 magnet and a low speed magnet, means operating when said high speed magnet is energized to connect said cylinder with a source of fluid pressure through a restricted orifice, means operating when said medium 35 speed magnet is energized and said high speed magnet is de-energized to connect said cylinder with said medium speed valve and with said source of fluid pressure and restricted orifice, means operating when said 40 low speed magnet is energized and said high speed and medium speed magnets are de-energized to connect said cylinder with said low speed valve as well as with said source of pressure and restricted orifice, means operating when said 45 low speed magnet is energized and said high speed valve when the speed of the train exceeds a given low value, said medium speed valve when the speed exceeds a given medium value, and said high speed valve when the speed exceeds a given high value, means for energizing 50 said high speed magnet under clear traffic conditions and said medium speed magnet under caution traffic conditions, a normally open acknowledging switch, means for energizing said low speed magnet if said switch is closed under danger traffic conditions before 55 said train governing mechanism is set into operation, and means for subsequently keeping said low speed magnet energized as long as danger conditions exist.
12. Train control apparatus comprising a cylinder, a movable member associated with said cylinder and responsive to variations of pressure therein, a contact operated by said member, train governing mechanism controlled by said contact; a high speed valve 60 constantly connected with said cylinder, a medium speed valve, a low speed valve, all of which valves are biased to the closed position, a high speed magnet, a medium speed magnet and a low speed magnet, a high speed pilot valve controlled by said high speed magnet and operating when the magnet is energized to connect said cylinder with a source of fluid pressure through a restricted orifice, a medium speed pilot valve controlled by said 65 medium speed magnet and operating when the magnet is energized and said high speed magnet is de-energized to connect said cylinder with said medium speed valve and with said source of fluid pressure and restricted 70 orifice, a low speed pilot valve controlled by said low speed magnet and operating when the magnet is energized and the other two magnets are de-energized to connect said cylinder with 75 atmosphere but not with said source of pressure; a centrifugal device operatively connected with an axle of the train, and means operated by said device for opening said low speed valve when the speed of the train exceeds a given low value, said medium speed valve when the speed exceeds a given medium value, and said high speed valve when the speed exceeds a given high value.
11. Train control apparatus comprising a cylinder, a movable member associated with said cylinder and responsive to variations of pressure therein, a contact operated by said member, train governing mechanism controlled by said low speed magnet and operating when the magnet is energized and the other two magnets are de-energized to connect said cylinder with said low speed valve as well as

with said fluid pressure source and restricted orifice, said pilot valves operating when all three magnets are de-energized to connect said cylinder with atmosphere but not with 5 said source of pressure, and means for opening said low speed valve when the speed of the train exceeds a given low value, said medium speed valve when the speed exceeds a given medium value, and said high speed 10 valve when the speed exceeds a given high value, means for energizing said high speed magnet under clear traffic conditions and said medium speed magnet under caution traffic conditions, a normally open acknowledging 15 switch, means for energizing said low speed magnet if said switch is closed under danger traffic conditions before said train governing mechanism is set into operation, and means for subsequently keeping said low speed magnet 20 energized as long as danger conditions exist.

13. Train control apparatus comprising a cylinder, a movable member associated with said cylinder and responsive to variations of 25 pressure therein, a contact operated by said member, train governing mechanism controlled by said contact; a low speed magnet, a normally closed low speed valve, means operating under traffic conditions requiring low 30 speed for connecting said cylinder with atmosphere if said magnet is de-energized but for connecting said cylinder with said valve and also with a source of fluid pressure through a restricted orifice if the magnet is 35 energized, means for opening said valve when the speed of the train exceeds a given low speed, a normally open acknowledging switch, means for energizing said magnet if said switch is closed under traffic conditions 40 requiring low speed before said train governing mechanism is set into operation, and means for subsequently keeping said magnet energized as long as traffic conditions requiring low speed persist.

14. Train control apparatus comprising a

cylinder, a movable member associated with 45 said cylinder and responsive to variations of pressure therein, a contact operated by said member, train governing mechanism controlled by said contact; a low speed magnet, a normally closed low speed valve, means operating under traffic conditions requiring low speed for connecting said cylinder with atmosphere if said magnet is de-energized but for connecting said cylinder with said valve and also with a source of fluid pressure 50 through a restricted orifice if the magnet is energized, means for opening said valve when the speed of the train exceeds a given low speed, a normally open acknowledging switch, a relay having a contact closed under 55 conditions requiring low speed, a contact operated by said magnet and closed only when the magnet is energized, a pick-up circuit for said magnet including said switch and said relay contact, and a holding circuit for said magnet including said relay contact and said magnet operated contact.

15. Train control apparatus comprising a cylinder connected with a source of fluid pressure through a restricted orifice, a normally closed valve connected with said cylinder, a centrifugal device operatively connected with a wheel of the train, means operated by said centrifugal device for opening said valve when the speed of the train exceeds a given 70 value, a movable member responsive to variations of the pressure in said cylinder, a contact operated by said member, a second restricted orifice interposed between said cylinder and said valve to delay the operation of said contact in response to the opening of the valve, a check valve connected around said second restricted orifice to permit quick charging of said cylinder from said source when said first valve closes, and train governing mechanism controlled by said contact.

In testimony whereof I affix my signature.

LLOYD V. LEWIS.
